DESIGN FOR A COMBINED HOLDER AND RECEPTACLE THEREFOR, OR THE LIKE

Charles L. Fordyce, New York, N. Y., assignor to M. Halprin, Inc., Brooklyn, N. Y., a corporation of New York

Application April 17, 1943, Serial No. 109,989

Term of patent 7 years

To all whom it may concern:

Be it known that I, Charles L. Fordyce, a citizen of the United States and a resident of New York, in the county of New York and State of New York, have invented a new, original, and ornamental Design for a Combined Holder and Receptacle Therefor, or the like, as shown, of which the following is a specification, reference being had to the accompanying drawing, forming a part thereof.

and receptacle therefor, or the like, showing my new design;

The dominant features of my design reside in the portions shown in full lines.

I claim:

The ornamental design for a combined holder and receptacle therefor, or the like, as shown and described.

CHARLES L. FORDYCE.
